UNITED STATES PATENT OFFICE

122,474

DESIGN FOR A TWIN WAFFLE IRON OR SIMILAR ARTICLE

Chauncey E. Waltman, Chicago, Ill., assignor to
Dominion Electrical Manufacturing, Inc.

Application July 16, 1940, Serial No. 93,718

Term of patent 7 years

To all whom it may concern:

Be it known that I, Chauncey E. Waltman, a citizen of the United States, residing in the city of Chicago, county of Cook, and State of Illinois, have invented a new, original, and ornamental Design for a Twin Waffle Iron or Similar Article, of which the following is a specification, reference being had to the accompanying drawing, forming a part thereof.

Figure 1 is a top plan view of a twin waffle iron or similar article, showing my new design;

Figure 2 is a front elevational view, partly in section; and

Figure 3 is a side elevational view thereof.

I claim:

The ornamental design for a twin waffle iron or similar article, substantially as shown.

CHAUNCEY E. WALTMAN.
